ELECTRIC SWITCH

Paul A. Heady, South Pasadena, Calif.

Application October 22, 1938, Serial No. 236,466

6 Claims. (Cl. 200—9)

This invention relates to an electric switch of the multiple contact type.

An object of the invention is to provide a compact and longer lived switch of the type stated.

Another, and more specific object, is to provide a switch construction having a set of circuit making and circuit breaking brushes formed of strips of resilient metal which are arranged in such a manner that the same strips which open and close the circuit also constitute pawls that cooperate with ratchet elements to prevent a backward rotation of the switch, thereby adding to the compactness and simplicity of the structure.

Still another object is to arrange and proportion the resilient brush arms in such a manner that they will be only slightly flexed by the operation of the switch, and therefore will maintain their resiliency for a long period of active use.

By this invention a single switch construction is provided which can be used to control two different circuits, one circuit being controlled by rotating the switch progressively in one direction and the other circuit being controlled by rotating the switch with partial turns in the reverse direction.

This switch is particularly well adapted for use as a means to control the current for floor lamps. The switch may be mounted around the tubular standard of a floor lamp thus economizing space.

Other objects, advantages and features of the invention will hereinafter appear.

Referring to the accompanying drawing, which illustrates what is at present deemed to be a preferred embodiment of the invention,

Fig. 1 is a section taken on line 1—1 of Fig. 2, except that the brushes are shown in elevation, and the wiring diagram is also included.

Fig. 2 is a section on line 2—2 of Fig. 1, a fragment of the supporting means being included in the view and shown in side elevation.

Fig. 3 is a side elevation of a floor lamp the filaments of which are controlled by the switch construction to which the invention pertains.

Referring in detail to the drawing, the casing of the switch comprises two cooperating, disk-like members 10 and 11, the member 10 being of the greater diameter and having a laterally extending peripheral flange 12. The disk 11 likewise has a peripheral, lateral flange or annular extension 13 around which closely fits the flange 12 of the larger disk which forms a cap member when the two disks are in the assembled relation, as shown in the drawing. The members 10 and 11 are of

non-conducting material, but carry certain conductors hereinafter described.

Around its central portion the stationary disk 11 has a hub-like flange 14 which projects from the same face of said disk as its peripheral flange 13. By means of said flange 14 this disk is fixed to a support 15 which, in the present instance, is a part of the standard 16 of the floor lamp shown in Fig. 3. From this view it will be seen that the turnable cap member 10 appears to be a symmetrical part of said standard and that the necessity of using switch buttons of a more or less unsightly character is avoided. Said member 10 is easily reached by the hand from all sides.

The cap member 10 has an annular flange 18 which, when the parts are assembled, occupies a spaced intermediate relation to the flanges 13 and 14, and projects from the same face of said disk 10 as does its peripheral flange 12. In the space between said flange 18 and the hub-flange 14 there is located an inner disk member 19 which is turnably mounted upon the hub-flange 14, said disk 19 having an annular peripheral flange 21 which is in a spaced relation both to the hub-flange 14 and the flange 18 of the manually turnable disk 10.

The relatively thick flange or annular extension 13 of the stationary disk 11 has elongated interior recesses 25, three of these being shown in Fig. 1. The lengths of these recesses extend in the direction of the circumference of the flange in which they are formed and the end portions of each of these recesses are shown furnished with indentations or seats 26 and 27. Into these seats are fitted bent portions of brushes which consist of resilient strips of metal, three brushes 31, 32 and 33 being thus provided.

By preference and as shown these three brushes are all of identical construction, each consisting of an outer straight run 34 terminating in a curl 35 which fits into the concavity afforded by one of the seats 27, while at the opposite end of said straight run the strip is convexly rebent, the convex side of the bend being fitted into the concavity formed by one of the seats 26. The rebent inner free end portion 37 of each of the aforesaid three brushes is somewhat curved, as shown, its concave side being directed towards the center of the device and its free end portion forming a contact. The convex bends in the brushes fit the seats provided for them and cause the brushes to last longer than would be the case if they were angularly bent. The brush 31 is supplied with current from the feed wire 38, the

brush 32 delivers current through wire 39 and the brush 33 delivers current through the wire 40.

The contact making means afforded by the free end portions of the aforesaid three brushes co-operate with the facing strip 41 of conducting material which is mounted exteriorly upon the annular flange 18, said brushes also cooperating with the non-conducting segment of said flange which intervenes between the end portions of said 10 conducting strip 41. Said flange 18 has a series of four circumferentially spaced ratchet shoulders 42 which divide it externally into quadrants. Said facing strip 41 is a strip of conducting metal which is shaped to conform to said quadrants 15 and shoulders and has inwardly directed anchoring end portions 41a directed into seats provided for them in the flange 18.

In addition, the flange 18 is provided with a series of ratchet shoulders 45 which divide it 20 interiorly into eight segments. The purpose of these interior shoulders is to impart at times a clockwise turning movement to the inner disk 19. In order to accomplish this the flange 21 of said inner disk carries a spring pawl 46 which cooperates with said interior ratchet shoulders. The flange 21 also carries externally a semicircular conductor strip 47 one end portion of which is led through the flange and is continued inwardly as a combined pawl and contact making arm 48, 25 while the opposite end portion of said strip 47 forms a like arm 49 having similar functions. Said arms 48 and 49 act as conducting brushes in cooperation with two identical conducting facing strips 51 and 52 which are carried by the hub 30 flange 21. Each of these strips consist of a piece of metal which is partly embedded in and partly overlies the insulating material of which said hub flange is formed, thereby forming four segmental conducting surfaces between which intervene, in 35 alternation, four segmental nonconducting surfaces. A branch 61 of feed wire 38 supplies current to said strip 51 and a current delivery wire 62 leads from said strip 52.

The hub-like flange 14 has exterior, equally spaced, ratchet shoulders 71, eight of these shown, to cooperate with the combined brushes and pawls 48 and 49.

Describing further the wiring shown in Fig. 1, current delivered by the wire 62, already mentioned, passes through the filaments 63 of the two lamps 64 and thence out to the main wire 65. The lamp 66 is of a greater wattage than either of the lamps 64. One of its filaments 67 is supplied by the wire 39 whenever current flows 50 through this wire, the current after passing through said filament passing through a branch wire 68 to the negative line 65. The filament 67 is a 200 watt filament and said lamp 66 also has a 100 watt filament 69. The latter filament is supplied by the aforesaid wire 48 which also continues its current through the negative branch wire 68.

In Fig. 3 the lamp standard 16 is shown furnished with an upward extension 16x upon which 65 is mounted the various lamps and their filaments above described, the reference numerals on the latter view corresponding with those of the wiring diagram.

In the operation of the device, when it is desired to energize the 100 watt filament 69 of the lamp 66, the cap member 10, as positioned in Fig. 1, is turned anti-clockwise a quarter of a rotation thereby causing the quadrant of insulating material which is engaged by the tongue 37 70 of the brush 31 to move out of contact with said

tongue and the conducting strip 41 to take its place. This movement will put the middle brush 32 out of service but will allow the third brush 33 to remain in contact with said conducting strip so that current supplied from feed wire 38 5 through brush 31 will pass through the strip 41 and thence by way of wire 40 through the aforesaid filament 69 and thence by way of the wire 63 to the main negative wire 65. Continuing the same turning movement an additional quarter 10 turn will bring the brush 33 into engagement with the segment of insulating material and cause the intermediate brush 32 to engage one end segment of the conducting strip 41 while the brush 31 engages the opposite end segment of said 15 strip. This will cause the current to be turned off from the filament 69 but will permit current fed to the brush 31 to pass thence through the strip 41, intermediate brush 32 and wire 39 to the 200 watt filament 67 and thence by wire 68 20 back to the main negative wire 65. Furthermore, it is evident that by turning the cap member 10 an additional quarter turn in the anti-clockwise direction all three of said brushes will be brought into contact with the conducting strip 41 thus 25 energizing both filaments of the lamp 66.

During all the switching positions that have thus far been described the two lamps 64 may be on or off because the inner brushes 48 and 49 may previously have been adjusted to open or close 30 the circuit to the latter lamps, said two brushes being advanced by rotating the cap member short steps in the clockwise direction without affecting the flow of current to the filaments 67 and 69.

The way in which the aforesaid short reverse 35 clockwise turning movements of the cap member 10 may be utilized to turn on or off the current through the two lamps 64 will be better understood if it is first noted that the internal ratchet shoulders 45 of the cap member flange 18 can 40 thus be caused to act upon the spring pawl 46 of the flange 21 of the internal disk 19 to turn the latter disk step by step; it being necessary also to note the fact that said internal ratchet shoulders are closer together (half as far apart) 45 as the external ratchet shoulders 42 of the same member, and the ratchet shoulders 21 of the hub-like flange are still closer together, dividing the latter flange into eight segments. Furthermore, the inner brushes 48 and 49 are diametrically opposite to each other so that at all times they both engage either insulating or else conducting segments of the flange 21. In Fig. 1 both these brushes are shown on non-conducting segments, but by turning the cap member 10 having 50 the flange 18 only a one-eighth turn in the clockwise direction (which will not necessarily alter the functioning of its three brushes 31, 32 and 33), the spring pawl 46 will be acted upon thus turning slightly the inner disk 19 and causing 55 the brush 46 to engage the adjacent exposed end portion of the conducting strip 51, while its mate brush 49 will be caused to engage the diametrically opposite exposed portion of the conducting strip 52. Owing to said brushes 48 and 49 being 60 connected by the conducting strip 47, this strip and its brushes collectively considered form a conductor which, under this condition, will bridge the gap between the conductor strips 51 and 52, with the result that current from feed wire 61 65 70 will pass through the strip 51 and thence through said brushes and their uniting strip to the strip 52 whence the current will pass through wire 62, lamps 64 and thence to the negative line wire 65.

From the foregoing description it will readily 75

be seen that by rotating the cap member 10 clockwise a one-eighth turn from any one of its four lighting current controlling positions the lamps 64 may be turned from on to off, or vice versa. 5 The ratchet shoulders 71 of the hub-like flange 14 prevent progressive anticlockwise rotation of the cap member from disturbing the position of the flange 21 of the inner disk 19.

I claim:

- 10 1. In a switch construction, two relatively rotatable members each having an annular portion in a concentric radially spaced relation to that of the other thus providing an annular space between them, one of said members having a recess adjacent to said annular space, a brush consisting of a leaf spring having a bent portion anchored in said recess and a free end portion contacting with the other member at the opposite side of said annular space, the latter member having conducting and non-conducting portions contacted by said brush, and current conducting means electrically connected with said brush and conducting material.
- 15 2. In a multiple switch construction, a mounting means, a stationary disk mounted thereon, said disk having a hub-like flange and a peripheral flange both projecting laterally from the same face thereof, a spacious annular clearance being thereby provided between said flanges, a 20 manually turnable member mounted upon said stationary disk, said turnable member having an annular flange in a spaced intermediate relation to both the aforesaid flanges of said stationary disk, an inner disk member turnably mounted 25 upon said hub-like flange, said inner member having an annular flange intervening between said hub-like flange and the flange next radially outward therefrom, circuit making and breaking means occupying all the annular spaces between 30 said annular flanges and operable by relative turning movements of said members, and current conducting means connected with said circuit making and breaking means to distribute the current to a plurality of points of use.
- 35 3. In a multiple switch construction, a member having an annular portion, a first, second and third brush of conducting material mounted internally upon said annular portion in an insulated relation to each other, the first and third brushes being located substantially diametrically opposite to each other and the second being located substantially midway between the other two with

respect to the circumference of said annular portion, an internal generally circular part the periphery of which is spaced radially inward from the inner periphery of said annular portion, approximately three-fourths of the periphery of 5 said circular part having a continuous face of conducting material and the remaining portion of said periphery having a face of nonconducting material which occupies the interval between the opposite end portions of said face of conducting material, said annular portion and circular member being relatively rotatable to move all of said brushes progressively across said two face portions, and current conducting means connected with all of said brushes. 10

4. In a multiple switch construction, a member having an annular portion, a first, second and third brush of conducting material mounted internally upon said annular portion in an insulated relation to each other, said three brushes 20 being consecutively grouped in a spaced relation to each other and leaving the remainder of the circumferential extent of said annular portion unoccupied by any of them, an internal generally circular part the periphery of which is 25 spaced radially inward from the inner periphery of said annular portion, a portion of the periphery of said circular part having a face of conducting material and the remaining portion of said periphery having a face of non-conducting 30 material which occupies the interval between the opposite end portions of said face of conducting material, said annular portion and circular member being relatively rotatable to move all of said brushes progressively across said two face portions, and current conducting means operatively 35 related to all of said brushes.

5. In an electric switch, a brush-mounting member comprising a casing having an annular portion furnished with an interval circumferentially elongated recess, each end of said recess having therein a seat in its end wall, and a brush consisting of a bent strip of metal, said strip having a run opposite end portions of which are seated in said seats, said strip also having a free 45 portion to perform the circuit making function.

6. The subject matter of claim 5 and, at least one of said seats opening out at a side of said annular portion of the casing to allow said strip of metal to be moved in an edgewise manner into 50 its operative position in said seat.

PAUL A. HEADY.
